TIE PLATE AND RAIL RETAINING CLIP

Frederick A. Preston, Lake Forest, Ill., assignor
to The P & M Company, Chicago, Ill., a corpora-
tion of Illinois

Application April 11, 1932, Serial No. 604,509

8 Claims. (Cl. 238—304)

This invention relates to improvements in devices for supporting and retaining a railroad rail in its proper position in a trackway and more particularly to the general class of such devices which consists of a tie plate having ribs or other forms of abutments thereon, to prevent lateral movement of the rail, and means removably engaged with the plate and projecting over a base flange of the rail to maintain a desired engagement of the plate and rail.

One of the principal objects of the invention is to provide an improved combination structure of the above character in which the means on the tie plate for providing a lateral abutment for the rail, and the rail retaining clip associated with said abutment, are so formed and engaged with each other as to simplify the manufacture of the tie plate and clip, and which make it practicable to form the tie plate with relatively low abut-

ments. Another object of the invention is to provide a tie plate having an abutment thereon which is so formed as to provide for convenient locking engagement with a rail retaining clip member, which will permit application of said clip at various locations longitudinally of the said abutment, and which also provides for firm engagement of the clip and said abutment without requiring the formation of key-ways in the said abutment, thereby making it practicable to employ key members of various widths, avoid the sharp edge portions of such key ways and in general to provide a more satisfactory abutment for devices of this character than heretofore employed.

Another and more specific object of the invention is to provide an improved tie plate and rail retaining clip in which a rail base abutment on the tie plate and a cooperating clip are so formed and engaged with each other that the clip is held in spring clamping engagement with said abutment without requiring engagement of the clip with the base portion of the rail. In this connection the invention contemplates a tie plate formed with an upstanding rib having an out-turned flange, which may be conveniently formed by the well known rolling process, the clip employed in connection with said rib being so formed that it can be driven transversely of the rib into clamping engagement with the out-turned flange of said rib.

Another object of the invention is to provide novel and improved tie plates and rail retaining clips therefor, which combination structure is particularly suitable for maintaining a rail in

proper position in a track, but which will permit the rail to move freely vertically within the range of the normal wave movements of the rail, so as to prevent such movements of the rail from displacing the cross-tie in the ballast of the roadbed. For example, the displacement generally known as "pumping" and the turning or "rolling" movements which are imparted to railway cross ties when the rail and tie structures are clamped in close contact with each other. A more specific feature of the invention contemplates a novel form of clip member whereby the clearance desired to be maintained between the top face of the rail base and the under face of the clip can be provided by offsetting the end of the clip, the said clip being offset with relation to its body in the direction required to provide the desired clearance between the clip and the rail.

Further and more specific objects of the invention will appear from the detailed description of the several embodiments of the invention illustrated in the accompanying drawings, wherein:

Fig. 1 is a plan view of a tie plate and rail retaining clip constructed in accordance with this invention and illustrating the base portion of a rail seated between the abutments of the tie plate.

Fig. 2 is a sectional view taken on line 2—2 of Fig. 1 to illustrate the clearances, provided for permitting the rail base to move vertically relative to the tie plate.

Fig. 3 is a sectional view taken on line 3—3 of Fig. 1 illustrating the means on the plate providing abutments for the rail retaining key.

Fig. 4 is a plan view of a modified form of tie plate and illustrating the use of rail retaining key members of different widths.

Fig. 5 is an end view of the construction shown in Fig. 4.

Fig. 6 is a fragmentary end view, in elevation, of a modified form of tie plate and a rail retaining key therefor, the latter of which is adapted to be formed of plate metal without involving bending operation.

Fig. 7 is a view in perspective of the rail retaining key member shown in Fig. 6, and

Fig. 8 is a view in perspective of a rolled metal bar having a cross-sectional configuration corresponding substantially to the shape of the clip member shown in Fig. 6, and from which clip members of any desired length may be cut.

Referring first to Figs. 1 to 3 inclusive of the drawings: The embodiments shown in said figures consist preferably of a tie plate, the base

55

portion 10 of which is clamped in close contact with the upper surface of a cross tie 11, by means of any suitable attaching devices, for example, lag screws 12. Formed on the upper face of the tie plate are spaced upstanding ribs 13 and 14 which provide abutments for the opposite edges of the base portion 15 of a railroad rail so as to prevent lateral movement of said rail. The upper edge portion of the rib 13 is turned inwardly 10 to provide a flange 16 which overlies the marginal portion of one base flange of the rail. The said flange 16 is preferably spaced from the upper surface of said base flange to provide a clearance 17 adapted to permit the base portion of 15 the rail to move vertically relative to the tie plate and thereby prevent the said vertical or wave movement of the rail, produced by the passing of traffic over the rail, from imparting vertical or pumping movements to the cross tie 20 11. The said vertical movements of the cross tie and likewise the turning or rolling movements of the tie in the ballast, which are present when a railroad rail is clamped tightly to the cross tie, not only loosens the tie in the ballast 25 of the road-bed, but also permits the ballast to work beneath the cross tie in a manner to impair the alignment and surface of the track. Such results are avoided in the present invention by the provision for relative movement between the base of the rail and the tie plate. 30

The rib 14 of the plate is formed to provide means for attachment of the rail-retaining clip member 18. In order to avoid the formation of key-ways through the rib and to provide a construction in which a relatively low abutment rib may be used and at the same time provide greater strength and rigidity, the upper edge of said rib is formed with an out-turned flange 19. This construction, in addition to providing a low shoulder or rib 14, which facilitates the application of the plate between the rail and cross tie, when the rail is in position, also provides a construction which avoids the punching of key-ways in the rib, permits the application of 45 the clip at various locations lengthwise of the rib, permits the use of clip members of various widths, and in general simplifies the manufacture of the plate in that the rib and the means for supporting the rail clip may be formed by 50 the well known rolling process. The outer edge of the lateral flange 19 is preferably curved, as indicated at 20, so as to provide rounded surfaces which facilitate the application of the clip member 18.

55 The clip member 18 consists preferably of a metal bar bent to provide jaws 21-22 which embrace and resiliently grip the lateral flange 19 of the rib 14. The jaw 21 is somewhat longer than the jaw 22 and extends over the upper edge 60 of the rib 14 so as to overlie the adjacent base flange of the rail. The end portion 23 of the clip which overlies the base flange of the rail is preferably offset relative to the main portion of the jaw 21 so as to provide the desired clearance 65 24 between the bottom face of the clip and the top face of the rail base. The clearance 24 is preferably equal to the clearance 17. In Fig. 2 of the drawings, the end 23 of the clip member is offset downwardly toward the base flange of 70 the rail, and the offset end provides a shoulder 25 which has a locking engagement with the inner edge of the rib 14 when the clip 18 is in its fully applied position. While the shoulder 25 for locking the clip on the rib and the desired 75 clearance 24 are obtained in the present em-

bodiment by the same offset portion of the clip, it will be obvious that in situations wherein it may be desirable to offset the end 23 upwardly, the shoulder 25 may be dispensed with or otherwise formed to snap over any suitable projection 5 on the rib 14.

By inspection of Figs. 1, 2 and 3 of the drawings, it will be apparent that the key member 18 is applied to its operative position by driving the key transversely of the rail until the shoulder 10 25 snaps over and into locking engagement with the inner edge of the rib 14. The key member maintains its position on the rib by reason of the resilient clamping engagement of its jaws 21-22 on the top and bottom surfaces of the 15 flange 19, the stressed engagement of the key being obtained by its movement to its operative position and without engagement with the base flange of the rail. The clip may be made from metal stock of any suitable thickness. The 20 thickness of the clip and the height of the shoulder are preferably such that there is but slight clearance between the jaw 22 of the clip and the top face of the tie-plate. In order to maintain the clip in its proper position during its movement to its applied position and to prevent displacement thereof longitudinally of the flange 19, the upper face of the base portion of the plate 10 is formed with a series of ribs 26 which serve as abutments for opposite faces of the 30 lower jaw 22.

In operation, the tie plate is normally fixed rigidly to the top face of the cross tie and the base flanges of the rail are positioned between the shoulders 13, 14 of the plate. The spring 35 retaining clip 18 is then driven to its applied position in the manner above described.

In Figs. 4 and 5, of the drawings, the tie plate 10a is formed adjacent opposite edges of the rail base with upstanding ribs which correspond in structure to the upstanding rib 14 of Figs. 1 to 3 inclusive. The said upstanding ribs of Figs. 4 and 5 are therefore designated as 14a-14a. In this form of tie plate, the transverse ribs 26, shown in Figs. 1, 2 and 3 inclusive, are omitted, 40 so as to make it practicable to use rail retaining clips of various widths. In Fig. 4 a rail-retaining clip 18 is illustrated corresponding in size and shape to the clip illustrated in Figs. 1, 2 and 3. A clip 18a of the same general contour, but of greater width, is illustrated in its applied position, it being applied to the upstanding rib at the opposite side of the rail base. The tie plate construction and the forms of the rail retaining clips shown in Figs. 4 and 5, except 45 for the distinction above noted, may be and preferably are the same in construction as the form of the invention shown in Figs. 1, 2 and 3 inclusive. The corresponding parts have therefore been indicated by the same reference numbers accompanied with an exponent "a". When removable clips are employed at opposite sides of the rail, the rail may be readily seated on the tie plates, when both clips are removed, without tilting the rail about its longitudinal axis. 50 With such a construction a rail may be removed from a track and another rail inserted therein without requiring removal of the splice bars at opposite ends of the rail. It is sufficient in such case to remove the joint splice bars at one end 55 only of the rail. The use of rail retaining clips on both sides of the rail presents a further advantage in that the height of the ribs 14a-14a may be so proportioned as to permit the rail retaining clips to frictionally engage the base 60 70 75 80 85 90 95 98 99 100

flanges of the rail when such engagement is desirable.

In Fig. 6 a further modification is shown in which the shoulder or rib member of the tie plate, 5 at one side of the rail, is formed with an out-turned flange 27 which instead of being disposed at right angles to the upstanding portion 28 of the rib is arranged to form an obtuse angle. The upper and lower surfaces 29 and 30 provide bearing surfaces for upper and lower jaws 31, 32 of 10 a retaining clip member 33. This clip member, instead of being formed by a bending operation, such as shown in connection with the previous figures, is made from plate material, the flange 15 receiving recess of the key being formed preferably by a suitable punching or shearing operation. When the clip is in its applied position any turning of the clip about the flange 27 as an axis moves the lower corner 34 and the corner portion 20 35 of the clip into binding position between the base of the tie plate and the lower surface 32 of said flange 27. The modified form of tie plate 10b may be formed at the opposite side of the rail with a rib corresponding to that shown 25 at 28 in Fig. 6 or with abutment ribs such as shown in any of the previous embodiments. The base portion 15b of the rail is applied to its operative position between the abutment shoulders of the plate 10b in the manner previously described. 30 The spring clips shown in Figs. 1 to 7 inclusive, instead of being formed in the manner previously indicated may be severed from a rolled metal bar 36 having the desired cross-sectional contour. In Fig. 8 a rolled metal bar 36 is shown 35 having a cross section corresponding in shape to the clip shown in Fig. 7. Clip members 33a of any desired length may be provided by severing them from the bar, one length of clip being indicated by dotted lines in Fig. 8 of the drawings.

40 I claim:

1. In combination, a tie plate member having a portion for insertion between a rail and cross tie and formed with an upstanding rib providing a vertical abutment for one edge of the rail base, 45 the said rib being formed along its upper edge with an out-turned flange and a resilient clip member having upper and lower jaws adapted to be driven transversely of said rib at any one of a plurality of locations into spring gripping engagement with the top and bottom surfaces of said out-turned flange and define a flange embracing recess of greater length than the width of said out-turned flange; one end of the upper jaw projecting over the upper surface of 50 said rail base and formed with a shoulder adapted to snap into locking engagement with said up-standing rib when the clip is driven to its applied position.

2. In combination, a tie-plate formed on its upper surface with a rib formed along its upper edge with an out-turned flange and providing a vertical abutment for one edge of a rail base, a rail retaining clip adapted for application to said rib at any one of a plurality of locations thereon 55 and formed with spaced jaws for gripping engagement with the top and bottom surfaces of said out-turned flange; one of said jaws extending over the upper edge of said rib and overlying the adjacent base flange of the rail, but with clearance between said jaw and the said rail base flange.

3. In combination, a tie-plate for supporting the base portion of a railroad rail and having a 60 relatively low rib thereon providing an abutment

for one edge of the rail base, which abutment is formed along its upper edge with an out-turned flange, a rail-retaining clip of substantially hook form having a long upper jaw and a shorter lower jaw and movable transversely of said abutment 5 at any one of a plurality of locations into spring clamping engagement with said out-turned flange; the end portion of the upper jaw of the said clip being offset downwardly relative to the top surface of said out-turned flange to provide 10 a locking shoulder engaged with said abutment and to position said offset end portion relative to the top surface of the adjacent base flange of the rail to permit limited vertical movement of 15 said rail base flange.

4. Supporting and retaining means for a railroad rail comprising in combination, a tie plate formed with an upstanding rib provided along its upper edge with an in-turned flange which overlies one base flange of the rail base, but is spaced 20 therefrom to permit limited vertical movement of the rail relative to the plate, a second upstanding rib for abutting engagement with the opposite edge of the rail base, which latter rib is of a height approximating the edge thickness of the 25 rail base and formed along its upper edge with an out-turned flange, and a resilient rail-retaining clip member having jaws movable transversely of said out-turned flange at any one of a plurality of locations longitudinally of the flange 30 into clamping engagement with the top and bottom surfaces thereof.

5. Supporting and retaining means for a railroad rail comprising in combination, a tie plate provided on its upper face with a relatively low 35 rib formed at its upper end with an outwardly turned flange and providing an abutment for one edge of the rail base, a rail retaining clip adapted to be driven transversely of said abutment to a position overlying the marginal portion of one 40 base flange of the rail and into clamping engagement with the top and bottom surfaces of said flange; the upper surface of said plate adjacent said rib being provided with a plurality of transversely extending ribs serving as reinforcements 45 for said abutment and to hold said clip against movement longitudinally of said rib.

6. Supporting and retaining means for a railroad rail comprising in combination, a tie plate formed on its upper surface with a rib having an 50 inner vertical side face to provide an abutment for one edge of the rail and having an outwardly projecting flange, and a stiff but slightly resilient rail retaining clip having upper and lower jaw portions which engage the upper and lower 55 faces of said flange, the upper one of which jaw members extends over the rail base and is provided with a shoulder to project below the inner edge of the rib so that when the clip is driven on the rib transversely thereof it will flex to allow the 60 jaw members to spread apart and then snap back into a close clamping engagement with the rib which retains the clip on the flange portion of the rib.

7. Supporting and retaining means for a railroad rail comprising in combination, a tie plate formed on its upper surface with an integral rib serving as an abutment for one edge portion of the rail, the upper portion of said rib being formed to extend upwardly and outwardly at an 70 obtuse angle to the inner face of the rib and the upper face of said out-turned portion being formed with a curvature in a direction transversely to the length of said rib, and a stiff but slightly resilient rail retaining clip member pro- 75

vided with upper and lower jaw members which engage the upper and lower faces of said flange, the upper one of which jaw members extends over the rail base and is provided with a shoulder 5 to project below the inner edge of the rib so that when the clip is driven on the rib transversely thereof it will flex to allow the jaw members to spread apart and snap back into a close clamping engagement with the rib which retains the clip 10 on the flange portion of the rib.

8. Supporting and retaining means for a railroad rail comprising in combination, a tie plate formed on its upper surface with a rib having an inner vertical side face to provide an abutment 15 for one edge of the rail and having an outwardly

projecting flange, and a stiff but slightly resilient rail retaining clip having upper and lower jaw portions which engage the upper and lower faces of said flange, the upper one of said jaw portions extending over the rail base and one of said jaw portions being formed with a locking shoulder and the rib being correspondingly formed to provide an interlocking engagement between said shoulder and rib so that when the clip is driven on the rib transversely thereof it will flex to 10 allow the jaw members to spread apart and spring back into a close interlocking engagement with the rib which retains the clip on the flanged portion of the rib. 5

FREDERICK A. PRESTON. 15
